CORPSE LIFTING APPARATUS

August B. Kubach, South Milwaukee, Wis.

Application February 2, 1939, Serial No. 254,230

9 Claims. (Cl. 27—28)

My invention relates to improvements in corpse lifting apparatus.

The object of my invention is to provide apparatus adapted for installation in the operating room of an undertaker's establishment to facilitate lifting corpses to the operating table, and removing them from such table for deposit in a casket.

More specifically, my object is to provide inexpensive equipment which may be quickly disassembled and reassembled, or adjusted to the requirements of any given lifting operation, and which may be quickly cleansed after each operation.

In the drawing:

15 Figure 1 is an elevation, partly in section, showing my improved apparatus as it appears when installed in an undertaker's operating room.

Figure 2 is a view of one of the slings, taken at right angles to Figure 1, and showing the lifting or evener bar in cross section, on line 2—2 of Figure 1.

Figure 3 is a sectional view drawn to line 3—3 of Figure 1.

Figure 4 is a sectional view of one of the head rests, drawn to line 4—4 of Figure 1.

Figure 5 is a view of the head rests taken at right angles to Figure 1, and showing the supporting arch rod in cross section.

Like parts are identified by the same reference characters throughout the several views.

A lifting bar having a central arch 10 is supported, by suitable tackle of ordinary type, from a turntable or derrick arm 11, swivelled to a support such as a bolt 12 depending from an overhead beam 13, which may form part of the ceiling of the operating room. Any suitable lifting tackle may be employed. Tackle blocks 15 and 16, and hoisting rope 17 may be used. The lower tackle block 16 has its hook 18 engaged in the eye pieces 19 of coupling clamps 20, which embrace the central portion of the arch 10, and are anchored thereto as indicated at 21 in Figure 3.

The lifting bar has horizontal end portions 22. It is preferably tubular in form, and at one end 45 has an interior slide 23 normally secured to the bar by a latch pin 24. The bar has a series of holes 25 through which the latch pin may extend to anchor the slide in any desired position of adjustment.

50 The slide 23 is rigidly connected with a head rest supporting rod, having a straight portion 28, an arcuate portion 29, which curves downwardly and inwardly, and a straight terminal portion 30, which extends inwardly with a slight downward 55 inclination.

An adjustable sleeve 32 is normally secured to the rod portion 30 by a thumb screw 33 (Figure 5). This sleeve is provided with upwardly and laterally curving wing arms 34, upon which cup-shaped head rests 35 are pivotally mounted on

substantially parallel pivot pins or bolts, so that the head rests may swing toward and away from each other, and be self adjusting to the head of the corpse at the base of the skull.

Each head rest has a depending ear 36, receivable between pairs of ears 37 carried by the associated arm 34, whereby the head rest may be connected with the arms by a pivot pin or bolt 38. Each head rest 35 has a central socket 39 to receive the hub of a removable lining bowl 40, 10 which will preferably be composed of rubber or equivalent flexible material, readily removable for cleansing purposes.

Collars 42 loosely encircle the end portions 22 of the lifting bar or rod, and are secured in desired positions of adjustment by latch pins 24, one of which is also used to anchor the head rest slide 23, and the other of which may similarly anchor a telescoping extension rod 43. Each of the collars 42 have depending rings 45 which encircle a bow-shaped rod 46, having terminal hooks 47 from which a sling 48 may be suspended by rings 49. The slings are formed of canvas, leather or equivalent flexible material adapted to be passed under the corpse, after which the rings 49 are hooked to the bow 46, as shown in Figure 2.

Ordinarily the two slings directly connected with the lifting rod will be respectively passed underneath the shoulders and hips of the corpse. If it is desired to also support the legs, another 30 sling may be similarly connected with the telescoping extension rod 43. The collars 42 are adjustable along the portions 22 of the lifting rod and the extension 43 when the latch pins 24 are removed, and therefore the slings 48 may be readily positioned with reference to the length of the body. Also, the head rests may be quickly adjusted by loosening the thumb nut 33 and moving the supporting sleeve 32 along the straight portion 30 of the head rest supporting rod. No extended 35 adjustment of the head rest will be required, for the reason that the slide 23 is also longitudinally adjustable.

I am aware that slings have heretofore been employed for the purpose of suspending a corpse 45 from a supporting pole, to be manually carried from place to place. But I believe I am the first to provide equipment which can safely be used in connection with suitable tackle, and in which the slings can be quickly adjusted to substantially balance the weight and then secured in such a manner as to absolutely preclude any shifting of the parts of the mechanism while the corpse is suspended.

Heretofore it has been customary to manually 55 lift the corpse to the operating table, or when depositing it from the operating table into the coffin. Quite frequently it is necessary to lift the corpse once or twice from the coffin in order to add or remove packing material, or readjust 60

the draperies. Ordinary hoisting mechanism cannot be successfully used, and an extremely large percentage of undertakers and their assistants are suffering from hernia because no means

5 have heretofore been provided to enable them to avoid these heavy lifting operations, with the body of the operator in an unfavorable position for lifting heavy weights.

I attach great importance to the central arch 10 of the lifting bar, since this tends to prevent the bar from sensitively tilting under slightly unbalanced loads. Also, the use of the latch pins 24 makes it impossible for the sling supports to slide along the lifting rod, and inasmuch as the 15 same latch pins are employed to secure the slide 23, telescoping rod 43, and the bows 46, these parts are not only securely connected but may be readily adjusted and secured with a minimum number of latch pins.

20 I also attach great importance to the simple construction of the head rests, whereby they may not only be readily adjusted, but whereby the lining members 40 may be quickly removed and cleansed.

25 With my improved construction, the derrick arm 11 may be swung to a position with the lifting rod directly over a corpse in a basket or on any wheeled conveyance, the slings adjusted about the body, and the body then lifted by means 30 of the tackle rope 47 until it can be swung over the operating table and deposited thereon. Similar operations in reverse order can be performed when the body is to be deposited in the coffin.

I claim:

35 1. Corpse lifting apparatus, including the combination with suitable lifting tackle, of a lifting rod having an upwardly arched central portion anchored to the lifting tackle, slings adjustably connected with its end portions and adapted to 40 be longitudinally adjusted along the lifting rod to substantially balance the load with reference to the point of connection with the lifting tackle, and means for temporarily securing the slings to the rod in various positions of adjustment along 45 its end portions, said upwardly arched central portion being adapted to limit tilting movements of the load when slightly unbalanced.

50 2. Corpse lifting apparatus, including the combination with suitable hoisting mechanism, a lifting rod having an upwardly arched central portion and apertured end portions, said central portion being operatively connected with the hoist slings adjustably connected with its end portions, and latch pins insertable in said apertures for 55 temporarily anchoring the slings in various positions along the end portions of the rod to sufficiently balance the load to allow it to be suspended in a substantially horizontal position by the upwardly arched central portion of the rod when lifted by said hoist, said slings being provided with collars mounted to slide on the lifting rod, and apertured to receive the latch pins.

60 3. Corpse lifting apparatus, including the combination with an overhead support, of a derrick member swivelled to said support, lifting tackle connected with the derrick member, a corpse lifting rod centrally arched and provided with coupling devices to be engaged by the lifting tackle, corpse supporting slings suspended from the end 65 portions of said rod, and a head rest adjustably connected with said rod, whereby the corpse may be sufficiently balanced with reference to the lifting tackle to allow it to be lifted and held in a substantially horizontal position by the cen-

trally arched portion of the rod during lifting and during transferring operations of the derrick member.

4. Corpse lifting apparatus, including the combination with an overhead support, of a derrick member swivelled to said support, lifting tackle connected with the derrick member at a point distant from the swivel connection with said support, a corpse lifting rod having coupling hook connection with the lifting tackle, means for limiting tilting movements of the rod with reference to the lifting tackle, bows suspended from said rod and provided with sling engaging hooks, and corpse supporting slings engageable with the hooks.

5. In a corpse lifting apparatus, the combination of a tubular lifting rod, coupling means secured to the central portion of the lifting rod and adapted to be connected with suitable lifting tackle, a slide adjustably mounted in one end of the lifting rod and provided with a hook-shaped extension, an adjustable head rest carried by the extension, sling supports depending from the lifting rod and adjustable thereon, slings detachably engageable with said supports, and means for anchoring said sling supports in various positions of adjustment along the lifting rod.

6. In a corpse lifting apparatus, the combination of a lifting rod centrally provided with coupling means for connection with suitable tackle, a head rest supporting slide connected with one end of the lifting rod, a leg supporting slide connected to the other end thereof, body supporting slings connected with the lifting rod, and latching means for temporarily securing the slings and slides in various positions of adjustment along said rod.

7. In a corpse lifting apparatus, the combination of a tubular sling supporting rod provided with apertures to receive a latch pin, a correspondingly apertured collar adjustable along said rod, an apertured slide adjustable within said rod, a head rest and sling, respectively connected with the slide and collar, and a latch pin adapted to pass through the rod, collar and slide to fixedly retain them in assembly.

8. In a corpse lifting apparatus, the combination of a lifting rod having an arched central portion and straight end portions provided with spaced apertures, an apertured collar adjustable along the lifting rod for registry of its apertures with those in the rod, a centrally apertured sling supporting bow suspended from said collar, a flexible sling having detachable hook connection with the ends of the bow, and a latch pin adapted to pass through the rod, collar and the bow to temporarily connect them.

9. In a corpse lifting apparatus, the combination with a suitable hoist and a lifting rod provided with means for limiting its tilting movement upon its connection with the hoist, of a slide adjustably connected with one end of the lifting rod and provided with a projecting hook-shaped end portion curving downwardly and inwardly with reference to the end of the rod, a head rest carrier adjustably connected with the extremity of said hook-shaped portion, and a pair of bowl-shaped head rests pivotally connected with said carrier and adapted to swing toward and away from each other on their pivotal connections, each of said bowl-shaped members being provided with a removable lining normally socketed therein and held by displacement by the socketed portion.

AUGUST B. KUBACH.
